GROVER F. BURG, OF ANN ARBOR, MICHIGAN

WASHER AND/OR DRIER FOR GOLF BALLS OR SIMILAR ARTICLES

Application filed December 8, 1930. Serial No. 500,854.

This invention relates to a washer and/or drier for golf balls or similar articles.

It is an object of this invention to produce a golf ball washer that will thoroughly wash, clean, and/or dry a golf ball in one operation.

In the drawings:

Fig. 1 is a top plan view of the washing and drying apparatus.

Fig. 2 is a side elevation of the gear end 10 of the machine.

Fig. 3 is a section along the line 3-3 of Fig. 1.

Fig. 4 is an end elevation showing the means for conducting the ball from the washer to the drier.

Fig. 5 is a detail of the worm.

Fig. 6 is a section along the line 6-6 of Fig. 5.

Referring more particularly to the drawings, it will be seen that the washing and drying apparatus is mounted in a casing 1, which casing is preferably a casting although it may be made from any suitable material. The casing in cross-section (Fig. 3) is S-shaped with a compartment 2 on one side which is arranged to receive the washing solution 3 and the washing apparatus which will be referred to later. The casing 1 likewise has a compartment 4 which is preferably closed at the top and opened to the atmosphere at the bottom in which is mounted the drying apparatus.

In the washing of a golf ball or a similar article it is essential that the washing or scrubbing apparatus come in contact with the entire surface of the ball if the same is to be thoroughly cleaned. To achieve this the washing apparatus is arranged to simultaneously clean and move the golf ball in such a manner that it does not rotate about a constant and definite axis, therefore the entire surface of the golf ball will be reached by the washing apparatus and washing solution. This is achieved by means of a pair of washing brushes 5 and 6 and a worm 7. The brushes 5 and 6 are mounted upon the shafts 8 and 9, the ends of which are journaled in the end walls of the compartment 2. The rotary brushes 5 and 6 are preferably made from a high grade of bristle and rotate in

opposite directions, that is, the brush 6 rotates counter-clockwise and the brush 5 clockwise so that the ball at all times is urged downwardly into engagement with the worm 7.

The worm 7 is journaled in to the end walls of the compartment 2 so that its axis is parallel to the axis of rotation of the two washing brushes 5 and 6. The worm 7 has non-rotatively mounted on the end thereof the driving gear 10 and the crank handle 11. The shafts 8 and 9 of the scrubbing brushes likewise are provided with suitable gears 12 and 13. The gears 12 and 13 mesh as at 14 and the shaft 9 also has mounted on the end thereof the pinion 15 which meshes with the main driving gear 10. The gear 12 is of lesser circumference than the gear 13, consequently the brush 5 rotates at a greater speed than the brush 6.

To keep the ball 16 in a path between the two washing brushes 5 and 6, a suitable guide is provided which preferably is in the form of a pair of parallel guide rails 17 and 18 which are fixed at each end in an end of the compartment 2. These guide rails 17 and 18, as nicely brought out in Fig. 3, are located slightly above the worm 7 circumferentially of the brushes 5 and 6 and parallel to the axes of the brushes and the worm. The compartment 2 is provided with a suitable cover 19 which is provided with the hole 20 in which the golf balls 16 are initially fed to clean and dry the same.

The golf ball 16 is carried from the opening 20 by means of the helical groove in the worm 7 to the opposite end of the compartment 2 where it passes out of the end of the compartment 2 through the opening 21 onto an inclined chute 22 which conveys the ball to the opening 23 in the end of the drying compartment 4. The drying apparatus is situated slightly below the level of the washing apparatus in order to permit the proper incline of the chute 22 so that the ball may be properly delivered from the washing apparatus to the drying apparatus. The inclined chute 22 is provided with an angular guide 24 which directs the ball 16 through the

opening 23 onto the drying apparatus worm 25.

The worm 25 is likewise journaled in the ends of the compartment 4 and has a large gear 26 mounted on the end thereof exterior of the compartment 4. A pair of drying brushes 27 and 28 is arranged in the drying compartment 4 parallel to each other and to the worm 25. The brushes 27 and 28 are mounted on suitable shafts 29 and 30 respectively which are likewise journaled at their ends in the ends of the compartment 4. The shafts 29 and 30 have mounted thereon the gears 31 and 32. The shaft 30 also carries the pinion 33. The gear 31 meshes with the gear 13. The gear 32 meshes with the gear 31 and the pinion meshes with the gear 26. The gear 32 is somewhat smaller than the gear 31 in circumference, hence, the brush 27 rotates at a greater speed than the brush 28. The brush 27 rotates in a counter-clockwise direction and the brush 28 in a clockwise direction. Hence, at all times the drying brushes force the golf ball downwardly upon the worm 25. As viewed in Fig. 2, the pinion 33 rotates the gear 26 and associated worm 25 in a direction opposite to that of the gear 10 and associated worm 7. The golf ball 16 is guided along the worm 25 and between the brushes 27 and 28 by a suitable guide means such as the guide rails 34 and 35 which are similar to the guide rails 17 and 18 in the washer compartment. The drying compartment 4 is provided adjacent the far end of the drying worm with a suitable chute 36 through which the completely washed and dried ball 16 is delivered. The end portion of the guide rail 34 which extends across the inner end of the discharge chute 36 is dropped below the top of the worm 25 so that the ball, upon reaching the end of the worm 25, can drop into the discharge chute 36.

To insure complete non-axial movement on the part of the golf ball as it is being carried along the helical groove in the worm so that the entire surface of the ball will be reached by the washing and drying brushes, the worms are provided at spaced intervals with suitable projections 40. These projections are sufficiently sharp to engage the golf ball during the rotation of the worm to move the same non-axially. The projections 40 give the article to be cleaned, such as the golf ball 16, a twisting or turning movement so that the entire surface of the ball, during the scrubbing and/or drying operation, will be scrubbed by the brushes. These projections 40 thus prevent the ball from traversing the entire length of the worm along a single given axis and effect a twisting movement on the part of the ball of such a nature that the axis of rotation of the ball is constantly changing during the scrubbing and/or drying operation.

In operation the golf ball is inserted

through the opening 20 whereupon it comes in contact with the worm 7. As the worm 7 is turned by the crank 11 it carries the ball 16 longitudinally of, and between, the scrubbing brushes 5 and 6, the rotary action of which urges the ball downwardly against the worm 7 during the scrubbing action. The level of the washing solution 3 is preferably just below the brushes and slightly over the top of the worm. The rotary action of the worm throws the washing solution against the balls. As the ball 16 comes in contact with each of the series of projections 40 it is turned non-axially, thus enabling the scrubbing brushes to reach the entire surface of the ball. Upon reaching the end of the worm 7 the ball passes through the opening 21 onto the chute 22 which directs the same through the opening 23 into the drying compartment 4 where the ball is taken up by the drying worm 25 and carried parallel to, and between, the drying brushes 27 and 28 which completely dry the ball. Upon reaching the end of the drying worm 25 the ball is ejected through the opening 36. It will be noted that this washing and drying operation can be a continuous operation on a continuously changing series of balls and need not be limited to a single ball per operation. It is understood that this apparatus can be used either for washing or drying or for both washing and drying. Further, the placing of the washing and drying apparatus side by side is merely a preferable arrangement.

From the above description it is evident that there is here produced a novel washing and/or drying device for golf balls or similar articles which is essentially characterized in that the ball traverses a predetermined path during the scrubbing and/or drying operation and during the traversing of this path is turned about a continually changing axis so as to subject the entire surface of the ball to the cleaning and/or drying operation.

I claim:

A device for cleaning spherical articles such as golf balls, comprising in combination a pair of rotary brushes, a rigid helically grooved worm, a pair of rigid guides positioned parallel to, and between, the worm and the brushes for carrying the spherical article along a straight line path between the worm and the brushes, and a plurality of projections positioned along the said worm for shifting the axis of rotation of the ball as it travels along the said worm, the said brushes being adapted to rotate in opposite directions to urge the said ball downwardly upon the said worm and projections.

In testimony whereof I affix my signature.
